MILKING MACHINE PULSATORE

Karl Gunnar Magni, Hellebo, Ronninge, Sweden,
assignor to De Laval Separator Company, New
York, N. Y., a corporation of New Jersey

Application August 3, 1936, Serial No. 93,982
In Sweden August 14, 1935

21 Claims. (Cl. 31—61)

My invention is an improvement upon the pulsator of the Forsberg Patent No. 2,042,300, dated May 26, 1936. In this patented pulsator the rate of pulsation is regulated by a fluid, preferably air, flowing back and forth between two closed containers, one at least of which is placed in a pulsator chamber which communicates with the pulsating pressure generated by the pulsator, whereby at least the one container, 5 by its variations of volume caused by the variations of pressure, acts on the members which regulate the distribution of higher and lower pressure. The said containers—at least one of them—must thus be expandable and are advantageously in the form of bellows acting on the valve mechanism which regulates the distribution of the pressures. Fig. 4 of the said patent shows an embodiment of the invention in which a valve spindle 55, provided with valves 53 and 54, is influenced at both ends by bellows 65 and 66. The present invention relates to a modification and further development of the pulsator according to Fig. 4 of said patent.

In the pulsator construction shown in Fig. 4 of said patent the valve 54 must be in the position illustrated to make a tight joint against the action of the atmospheric air. Its exact position in closed state, however, is determined by the position of the valve 53, which, in the 10 illustrated position, is kept in contact with its seat by the difference of pressure between the atmospheric pressure and the vacuum in chamber 62. While such a construction is operative, the distance between the seating faces of the 15 valves must correspond accurately with the distance between the valve seats, and this involves nicely measured accurate construction with some danger even then of failing to obtain the desirable positive sealing between one or the other 20 valve and its seat. One object of the invention is to obtain this positive sealing and to do so even though the parts may not be constructed with the degree of precision required in the prior construction.

Another feature of the prior construction is the provision of sealing collars like those numbered 77 and 78. Experience has shown that there is some danger that the valve system may be locked by these sealing members, particularly 25 when milk enters the pulsator. In any case these sealing members create undesirable forces acting on the spindle. Another object of the present invention is to dispense with sealing members of this character.

It is desirable, as recognized in said prior

patent, that the total quantity of the air enclosed in the containers should be kept approximately constant. The maintenance of this condition by mechanical means has not proved entirely satisfactory. Another object of the present invention is to provide a more satisfactory and reliable substitute.

The present invention attains the foregoing objects.

Further advantages are attained as compared 10 with known pulsators. Thus, in my improvement, each valve in its closed position is kept on its seat under the influence of the difference of pressure acting on the valve, so that a reliably tight joint is obtained independent of 15 great accuracy of measuring and independent of the wear of the valves and the seats.

The valves according to the present invention can also easily be made in such a manner 20 that a free passage from the side of the atmospheric pressure to the vacuum side is not formed during the moment of reversing, which is the case with all known pulsators without a slide.

Further, it is possible, in accordance with the 25 present invention, to make the valve housing in one piece, which effects a considerable simplification of the construction.

A further defect in known pulsators is that, 30 in a certain intermediate position—which may occur when the pulsator is not in operation—it fails to start. In a pulsator embodying the present invention, an operative starting position is insured.

Finally, the bellows according to the present 35 invention are so made that they can be fixed to their volume when the pulsator is at rest, by mechanical means, independent of the changes of tension which may, in the course of time, 40 take place in the highly elastic material (for instance rubber) of the bellows. The invention thus embodies a suitable fixing device for the bellows in their state of rest; that is, means to maintain the valve system in a fixed and pre-determined position, suitable for starting the 45 pulsator, when it is not in operation.

In the present invention, the chamber whose 50 volume can be changed and which contains the quantity of air closed to the atmosphere, is not formed by the bellows, as in the said prior patent, but by the space between the bellows and a rigid housing provided around it. By 55 this modification certain practical advantages are attained in regard to said fixing device.

The accompanying drawings show different embodiments of my invention.

Fig. 1 is an end view of the pulsator.

Fig. 2 is a longitudinal section through the pulsator on the line 2-2 of Fig. 1, the valve spindle being shown shifted to the left.

Fig. 3 is a longitudinal section through part of the length of the pulsator, on the line 3-3 of Fig. 1; the valves being shown in diagram.

Fig. 4 is an enlarged view of part of Fig. 2, showing the specific construction of the valves, the valve spindle being shown in the position it occupies a little before it completes its shift to the left.

Figs. 5 and 6 are longitudinal sectional views, similar to Fig. 4, of modifications of one of the valves.

Fig. 7 is another enlargement of part of Fig. 2, showing more clearly the bellows construction.

Fig. 8 is a view looking from the inside of one of the bellows toward its end piece.

Fig. 9 is an enlarged sectional view of a modified throttling device.

Fig. 10 is a detail sectional view of a modified connection between the end air chambers.

Fig. 11 is a fragmentary sectional view of part of Fig. 4 showing a transitory position of valve 14 in the operation of assembling the valves of Fig. 4.

Fig. 12 is a detail view of one of the end pieces of the bellows before it is applied to the housing.

The pulsator comprises a casing *a* having passages connecting respectively with sources of high and low fluid pressure (conveniently atmosphere and partial vacuum), other passages connected with two pairs of teat cups, a valve chamber, valve mechanism reciprocable therein, and pulsation chambers adapted, in the reciprocation of the valve mechanism, to connect different sets of teat cups simultaneously with the high and low pressure passages respectively and to connect each set of teat cups alternately with the high and low pressure passages: as hereinabove described in detail.

The chamber 1 always communicates with the atmosphere through a strainer 2 and a channel 3. The chamber 1 is provided with a double seating valve 4 mounted on a spindle 5. On each side 30 of the chamber 1 there is one of two pulsation chambers 6 and 7, into which the valve 4 alternately admits atmospheric air. The pulsation chamber 7 is separated from another pulsation chamber 8 by a sealing device 9. Beyond the pulsation chamber 8, reckoned in the axial direction of the spindle, is a chamber 10 which always communicates with the vacuum pipe of the system by a channel 11 and a nipple 12. Beyond the vacuum chamber 10 there is another pulsation chamber 13. The four pulsation chambers communicate with each other by pairs, as shown in Fig. 3; that is, chamber 8, through channels hereinafter described, communicates with chamber 6, and chamber 7, through similar channels, with chamber 13. The chamber 6 in turn communicates with two teat cups, and the chamber 13 with two other teat cups. The pulsation chambers 8 and 13 enclose valves 14 and 15, respectively, carried on the spindle 5, the said valves 40 opening and closing the communication between the pulsation chambers and the vacuum chamber 10.

At opposite ends of the valve system described are bellows 16 and 17, the interiors 18 and 19 75 of which communicate with the pulsation cham-

bers 6 and 13 respectively. The bellows are enclosed in chambers 20 and 21 respectively, which are closed to the atmosphere but communicate with each other by a channel 22, in which are arranged a series of throttling devices comprising partitions provided with fine holes 23, which can be made accessible to cleaning by removing a screw plug 24, which is provided with packing means 240.

The chambers 20 and 21 are closed to the atmosphere by end closures or hoods 25 and 26, which are tightly connected to the pulsator housing 28 by threads and packings 27.

As an alternative the channel 22 can be replaced by a straight channel 29 shown in Fig. 10 and located entirely inside the inner radius of the hoods 25 and 26. The screw 24 with its sealing disc can then be dispensed with, as the throttling holes 23 become accessible for cleaning by a needle or the like by removing one of the hoods 25 or 26 and possibly also one of the bellows. If it is desired to make the throttling openings 23 accessible without removing one of the bellows, it is necessary to increase the radius of the hoods 26 somewhat, as shown, so that the openings shall 25 not be positioned inside the radius of the bellows.

The construction of the valves 4, 14 and 15 and of the sealing device 9 is shown in Fig. 4, which shows part of the valve spindle 5 with valve bodies and valve seats on a larger scale. The sealing device 9 is conveniently made structurally identical with the valves 4, 14 and 15. Only part of the upper half of the spindle 5, and only the valves 14 and 15 and the sealing device 9 and the corresponding valve seats, are shown in the figure. As may be understood from the figure each of the valves substantially consists of a disc of some elastic material, for instance rubber, which is arranged in an annular groove 30 in the spindle. Each groove is surrounded by two flanges 31, over which the disc must be forced to place it in the groove. Each disc consists of an inner nave-shaped portion 32 (that extends within the spindle groove and is retained therein in its place on the spindle), a thinner central portion 33, and an outer heavier portion 34, which latter is the real sealing member and is intended to be in contact with the valve seat when the valve is closed. As previously stated, the valves 14 and 15 are located on opposite sides of vacuum chamber 10. Fig. 4 shows the position of the valve at the moment when the spindle 5 has been moved so far to the left (having almost completed its stroke) that the valve 15 has just come in contact with the seat 35. Under the influence of the difference of pressure (air pressure in chamber 8 and partial vacuum in chamber 10) acting on the valve, the valve 14 is still kept in contact with the valve seat 36. This is made possible by the great elasticity of the valve body, whose stress 40 tending to hold it in contact with its seat exceeds the said differential air pressure until the spindle 5 reaches the position shown in Fig. 4. In that position the elastic tension of the valve just barely suffices to balance the existing difference of pressure, so that when the spindle 5 moves farther to the left beyond the position shown, the valve 14 45 cannot yield any farther in relation to the spindle and separates from the seat 36 to permit equalization of pressures in chambers 8 and 10. At the end of the spindle's movement to the left, it occupies the position shown on the valve in broken lines and the valve 14 occupies the position 37 shown in broken lines. As the valve 14 is thus not opened until the valve 15 is closed, no free passage will 50

be formed from the atmospheric chamber 1 to the vacuum chamber 11 through the pulsator during the moment of reversing.

The operation just described refers only to the behavior of the individual valves. The following description fully explains the mode of operation of the pulsator as a whole.

With the spindle 5 at the left, as shown in Fig. 2, air entering through strainer 2 and channel 3 flows through chambers 1 and 7 and channels 68 and 70 to chamber 13 and the interior 19 of the bellows 17 and, by expanding the bellows, forces air out of the surrounding chamber 21 through the channel 22 toward the chamber 20 surrounding bellows 16. At the same time air is exhausted from inside of bellows 16 through chamber 6, channels 67 and 66, chambers 8 and 10, channel 11 and nipple 12.

Under these conditions, the head 48 of bellows 16 moves toward the right until it contacts the end of the spindle 5 and forces it toward the right, bending valves 4 and 15 (as valve 14 is shown in Fig. 4 but in the opposite direction), until valve 14 contacts with its seat (as valve 15 is shown in Fig. 4), and then still further to the right until valves 4 and 15 are forced away from their seats and the pressures on the two sides of each are equalized, allowing them to assume their normal positions on the spindle with valve 15 in the center of chamber 13 and valve 4 closing the opening between chambers 1 and 7.

Connections are now reversed and atmospheric pressure from chamber 1 can flow through chamber 6 into bellows 16 to expand it and force air from chamber 20 through channel 22 to chamber 21 and air from inside bellows 17 will be exhausted through chambers 13 and 10, channel 11 and nipple 12. The head of bellows 17 will soon contact with the right hand end of spindle 5 and push it toward the left, until the valves are forced to the position shown in Fig. 2 and the cycle will be repeated.

In the actual pulsator the spindle 5 has a loose fit or slight clearance in the guide bearing at the right sufficient to prevent the spindle from binding when it is guided, at the left, by the bow 56 of the spring 55.

The great elasticity of the valve bodies may, according to the invention, be utilized for the construction of an unparted or one-piece valve housing, as it is possible in assembly to force the valves through the openings of the valve seats, as indicated in Fig. 11, by forcing the valve stem and the valves carried thereby axially through the valve housing. The valve housing can therefore be made of one piece in which a central hole is bored, after which grooves are turned from the inside of this bore to form the chambers 1, 6, 7, 8, 10, and 13. To dismount the pulsator, the valve bodies are forced in the opposite direction through the openings of the valve seats.

The sealing device 9 consists, as before stated, of a valve disc of the same kind as the valves 14 and 15. The disc is movably arranged in a groove 39 in the spindle 5. The nave-shaped inner portion 32 forms a tight joint with the flange 31 in the position shown. After the valve disc 14 has assumed the position 37, the right side of the disc 9 is exposed to vacuum, while its left side is subject to atmospheric pressure. A completely tight joint is therefore insured by the difference of pressure acting on the disc 9. The outer heavier portion 34 of the disc 9 is inserted in a V-shaped groove 40, against the walls of which it is maintained by the existing difference

of pressure, so that here also a completely tight joint is insured.

When the spindle moves to the opposite position the disc 9 is deformed in a manner similar to the described deformation of discs 14 and 15, so that a tight joint is maintained between the disc and its seat in the valve housing until the moment when the tension in the disc becomes sufficiently great to prevent it from further following the movement of the spindle. At this time, however, a reversal of the pressure on both sides of the disc 9 takes place, so that the nave 32 is quickly thrown over to the opposite surface of the groove 39. During this moment of reversal a leakage, although it be a very small one, occurs between the disc 9 and the spindle, because a certain play, amounting to some tenths of a millimeter, should be allowed between the disc and the spindle in radial direction. After the moment of reversal a completely tight joint is established. The amount of air leaking past the sealing device during the moment of reversal is very small, being limited to one or perhaps a few per cent of the amount of air passing through pulsators having valve discs of the construction heretofore used. It is possible to avoid this insignificant leakage by using a sealing member 9 which has so great elasticity and shape-changing capacity that the portion of the tightening member fitting to the spindle can follow the whole movement of the spindle without causing too great a resistance.

Alternatively the valve 14 can be modified as shown in Fig. 5. As so modified it comprises a ring-shaped portion 41 of approximately square section, which at its outer edge is connected to a disc-shaped annulus 42, which extends into a groove 43 in the spindle. The spindle 5 is provided with a flange 44 which is positioned to contact with a shoulder 45 on the inside of the annular portion 41. In tensionless state the valve body has the shape indicated by dotted lines at 46. In the position shown in full lines the valve body is maintained on its seat 36, by pressure difference, against the elastic tension of the disc 42. When the spindle moves a short way to the left the part 41 is by the flange 44 forced to leave the seat 36 so that the valve opens. As compared with the embodiment shown in Fig. 4 the latter embodiment has the advantage that the valves are forced to open at an accurately fixed position of the spindle independent of the elastic tension of the valve body. Further, the valve body proper may be made of a less elastic material than the disc-shaped portion 42, or even of entirely unelastic material.

Other embodiments of the valve body are within the scope of the invention. For example, it is practicable to substitute for the valve 41 the valve shown in Fig. 6, in which the parts 41' and 42' connect with each other at a greater radial distance from the spindle than the corresponding parts 41 and 42 shown in Fig. 6. With this arrangement the part 42' can be allowed to be considerably less elastic than the corresponding part 42 of Fig. 5. Also other constructions are possible. In order, however, to meet the requirements of the present invention, that portion of the valve body which is to contact with the valve seat must be movable within certain limits relative to the valve spindle and is preferably elastically connected therewith. This last mentioned condition is not absolutely necessary, as the valve body alternatively may be slidably connected with the spindle. A slide-connection, however, may be

less suitable as it is open to the objection that the friction can hardly be kept at a constant and desirable low value.

In Figs. 1 and 2 it is assumed that the chamber 1 for air is provided with a single valve disc 4 which alternately contacts with valve seats arranged on both sides thereof. Such a construction may be used to advantage if the valve disc is of the type shown in Fig. 4 and thus symmetric. The valve disc is then, however, subjected to greater changes of shape than the discs 14 and 15, because in its two end positions the disc 4 is kept on the valve seat, by the difference of pressure, until the spindle has approached the opposite end position. In certain circumstances it may therefore prove advantageous to replace the common valve disc 4 by two valve discs cooperating each with its valve seat. This expedient is necessary in case valve discs of a construction similar to that shown in Figs. 5 or 6 be used.

Each of the bellows 16 and 17 comprises two end pieces 47 and 48, connected one with the other by a substantially cylindrical plaited wall 49, as shown in Fig. 7. The plaiting of the said wall 49 is determined by two spiral springs 50 and 51 provided outside and inside the same, which tend to keep the bellows stretched, so that the end piece 48 contacts with the cap 26 when the pulsator is at rest. The end piece 47 provided with a horizontal flange to which the wall 49 is fixed. The end piece 47 is made of rather stiff rubber or similar material and the cylindrical portion that fits around the nipple-like portion 52 of the pulsator housing 4 is so made that, when free and in tensionless state, it is slightly tapered or conical, as shown in Fig. 12. When this piece is forced onto the part 52, it is stretched to a cylindrical form and then tightly hugs the part 52.

The end-piece 48 is a more or less rigid circular disc which at the circumference is tightly fixed to the bellows wall 49. As the end wall 48 moves forth and back in the hood 26 during the operation of the pulsator, it may be provided with a lining in order to prevent the wall 49 from being worn by sliding against the inside of the hood 26. The lining may consist of a metal ring 53 as shown in Fig. 7.

On the end piece 48 there is in the interior of the bellows a lug-shaped hollow portion 54 (see Figs. 2 and 8) having at the base a somewhat smaller diameter than farther out, so that one end of a spring 55 can be retained therein. Spring 55 consists of three portions: the first wound like the main spring of a clock and having its inner turn adapted to fit closely in the groove in the lug 54, as shown in Fig. 2; the second a closely wound cylindrical portion as shown in Fig. 2, and the third a bow 56 embracing the neck 57 on spindle 5, as shown in Figs. 2 and 8. Outside the neck 57 the spindle is provided with a head 58, bounded by conical surfaces and retaining the bow 56. As shown in Fig. 2 only the left hand end of the spindle 5 is provided with a head 58.

The springs 50 and 51 and the spring 55, together with the flange 58, form a "fixing device" which—when the pulsator is not in operation—holds spindle 5 and the valves carried thereby enough toward one end to keep the valves closed so that the pulsator will start when connected to a source of partial vacuum. It also keeps the wall 48 in a fixed position so that the volume of the chamber 18 is fixed. As the bellows

17 is kept wholly stretched by the springs 50 and 51, the total volume of the two bellows is thus fixed, provided that there is no difference between the pressure inside and outside the bellows, which is of course the case when the pulsator is not operating. But when the volume of the bellows is fixed, the total volume of chambers 20 and 21 and the amount of air enclosed therein is also fixed. This constancy of volume is of great importance in counteracting possible small leakages in the walls of the chambers which, although they would not immediately entail difficulties of operation, nevertheless in the long run could cause disturbances by increasing or reducing the total quantity of air enclosed in the two chambers.

The tension of the spring 55 should of course not be so great that it counteracts to an appreciable degree the movements of the bellows during the operation of the pulsator. Nor should it be so great that it can reverse the valve system against the effect of the pressure differences operative upon the valves. The arrangement should act, and does act, to accomplish the purpose specified only when the pulsator is out of operation.

By the above described "fixing device", even if the tension of the spring 55 be very weak, a certain asymmetry of the pulsator results. By suitably determining the tension of the spring, the asymmetric forces caused by the fixing device may be reduced to such magnitude that the degree of non-uniformity of the pulsator can be reduced to as small a figure as one or two per cent, which will not in any way be objectionable.

This non-uniformity may also easily be compensated by making the throttle devices 23 asymmetric, so that a greater pressure is required to drive the air in the one direction than in the opposite direction. This asymmetry may easily be so determined that it exactly compensates the action of the spring 55. Such an asymmetry of the throttling devices 23 may be effected, for example, by making one end of each channel orifice somewhat larger than the other. If the channel consists of a hole bored in a plane wall, it may be sufficient to make the end of the bore more or less conical or bell-mouthed.

Asymmetry of the throttling devices may be effected in other ways. For instance, they may to advantage be arranged as shown in Fig. 9. The throttling devices are in this figure shown as short tubes each having one closed cone-shaped end provided with a central hole. These elements act to a certain degree as outflow nozzles, and a higher pressure is therefore required for the throughflow in the one direction than in the other, in order that a given amount of air shall pass through during the same time. To regulate the asymmetry some of the parts 59 may be turned in the one direction and some in the other, so that they more or less compensate each other.

When the pulsator is at rest its movable parts occupy the position shown in Fig. 2. They are brought into this position by the hereinbefore described fixing device as soon as the vacuum pipe is shut off and the difference of pressure in the pulsator ceases. The bow 56 is then kept by the conical flange 58 in the position shown, and, owing to the tension of the tightly wound spring 55, the wall 48 of the bellows is also kept in the illustrated position against the action of the springs 50 and 51. This position should be

so determined that, when the chamber 18 is connected with vacuum, the bellows as far as possible is completely compressed by the amount of air thereby expanding in the chamber 20. The amount of air passing through the throttling devices 23 during operation will thereby be as great as possible.

The dimensions and elasticity of the bow 56 should be so determined in relation to the head 58 that the bow can be forced over the head when the parts of the pulsator are assembled. The conical surface of the head 58 with which the bow 56 contacts should also have such a cone angle that the bow can be forced over the head in disassembling also.

The pulsation chambers 6, 7, 8 and 13 which, as described above, communicate by pairs with each other, also communicate with four nipples 61, 62, 63 and 64. Of these 63 and 64 communicate with each other over chamber 13. For establishing communication between the above-mentioned annular chambers and the nipples, channels in the form of vertical bores 65, 66, 67, 68, 69 and 70 are provided and are positioned tangentially in relation to the chambers 6, 7, 8 and 13. By this tangential location a connecting opening of sufficiently great area is obtained between each channel and the corresponding annular chamber with small dimensions of the valve housing.

In the foregoing description it has been assumed that the pulsator works with and is driven by a partial vacuum. It may, however, to the same advantage be used for generating pulsations between any two different absolute pressures, which may either be both lower than, or both higher than, or one above and the other below, atmospheric pressure. Also, it may be used with other media than air, for instance a liquid. In particular, it is not necessary that the fluid flowing back and forth between the two closed chambers should be air. This fluid may consist of some suitable liquid, which has certain advantages; for instance, it would permit of the more ample dimensioning of the throttling orifices.

The bellows need not have the specific construction described. For the springs 51 may be substituted two sets of rings, the Fig. 7 of the drawings being consistent, also, with such a modification. It is possible, indeed, to dispense entirely with rings or springs, as there is no considerable over-pressure in the bellows during operation.

What I claim and desire to protect by Letters Patent is:

1. A milking machine pulsator comprising a valve casing having a longitudinal bore provided with valve seats, the valve casing having passages adapted to communicate respectively with sources of high and low fluid pressure, a valve spindle reciprocable in said bore, two fluid pulsation chambers surrounding the spindle, valve mechanism carried by said spindle and adapted in one position of the spindle to connect one of said pulsation chambers with said high pressure fluid passage and the other of said pulsation chambers with the low pressure fluid passage and in its other position to reverse said connections, and a sealing device carried by the spindle and maintaining said pulsation chambers separated in both positions of the spindle.

2. A milking machine pulsator comprising a valve casing having a longitudinal bore provided with valve seats, the valve casing having pas-

sages adapted to communicate respectively with sources of high and low fluid pressure, a valve spindle reciprocable in said bore, two fluid pulsation chambers surrounding the spindle, valve mechanism carried by said spindle and adapted in one position of the spindle to connect one of said pulsation chambers with said high pressure fluid passage and the other of said pulsation chambers with the low pressure fluid passage and in its other position to reverse said connection, and a sealing device carried by the spindle and maintaining said pulsation chambers separated in both positions of the spindle, said sealing device comprising an annular disc surrounding the spindle and whose inner and outer marginal walls extend into grooves in the spindle and bore wall respectively.

3. A milking machine pulsator comprising a valve casing having a longitudinal bore provided with valve seats, the valve casing having passages adapted to communicate respectively with sources of high and low fluid pressure, a valve spindle reciprocable in said bore, two fluid pulsation chambers surrounding the spindle, valve mechanism carried by said spindle and adapted in one position of the spindle to connect one of said pulsation chambers with said high pressure fluid passage and the other of said pulsation chambers with the low pressure fluid passage and in its other position to reverse said connection, and a sealing device carried by the spindle and maintaining said pulsation chambers separated in both positions of the spindle, said sealing device comprising an annular flexible disc surrounding the spindle and whose inner and outer marginal walls extend into recesses in the spindle and bore wall respectively, one of said recesses being substantially wider than the thickness of the part of the disc position therein.

4. A milking machine pulsator comprising a valve casing having a longitudinal bore provided with valve seats, the valve casing having passages adapted to communicate respectively with sources of high and low fluid pressure, a valve spindle reciprocable in said bore, two fluid pulsation chambers surrounding the spindle, valve mechanism carried by said spindle and adapted in one position of the spindle to connect one of said pulsation chambers with said high pressure fluid passage and the other of said pulsation chambers with the low pressure fluid passage and in its other position to reverse said connection, and a sealing device carried by the spindle and maintaining said pulsation chambers separated in both positions of the spindle, said sealing device comprising an annular disc whose inner and outer marginal portions contact respectively with the spindle and the wall of the bore, said disc having a limited sliding play along one of the last two named members but contacting tightly with both members in either end position of the spindle.

5. A milking machine pulsator comprising a valve casing having a longitudinal bore provided with valve seats, the valve casing having passages adapted to communicate respectively with sources of high and low fluid pressure, a valve spindle reciprocable in said bore, two fluid pulsation chambers surrounding the spindle, valve mechanism carried by said spindle and adapted in one position of the spindle to connect one of said pulsation chambers with said high pressure fluid passage and the other of said pulsation chambers with the low pressure fluid passage and in its other position to reverse said connec-

tion, and a sealing device carried by the spindle and maintaining said pulsation chambers separated in both positions of the spindle, said sealing device comprising an annular flexible disc whose outer marginal portion extends into a groove in the bore of the casing, the valve spindle having a wide circumferential groove into which the inner marginal portion of the disc extends and along the bottom of which groove the inner marginal portion of the disc is adapted to slide in the movement of the spindle and against the side walls of which groove the inner portion of the disc is adapted to tightly seat in opposite end positions of the spindle.

15 6. A milking machine pulsator comprising a valve casing having a longitudinal bore provided with valve seats, a valve spindle reciprocable in said bore, a high pressure chamber surrounding the spindle and adapted to communicate with a 20 source of high pressure, a pulsation chamber surrounding the spindle on one side of the high pressure chamber, a second pulsation chamber surrounding the spindle on the other side of the high pressure chamber, a third pulsation chamber 25 surrounding the spindle beyond the second pulsation chamber and connected with the first pulsation chamber, a low pressure chamber surrounding the spindle beyond the third pulsation chamber, a fourth pulsation chamber surrounding the spindle beyond the low pressure chamber and connected with the second pulsation chamber, valve means carried by the spindle and adapted to connect the high pressure chamber alternately with the pulsation chamber on opposite sides thereof, a valve carried by the spindle adapted to alternately connect and disconnect the third pulsation chamber with the low pressure chamber, a valve carried by the spindle and adapted to alternately connect and disconnect the fourth pulsation chamber with the low pressure chamber, and a sealing device surrounding the spindle and separating the second and third pulsation chambers.

7. A milking machine pulsator comprising a valve having a longitudinal bore, a valve spindle reciprocable therein, fluid passages adapted to communicate respectively with sources of high and low pressure, a high pressure chamber surrounding said spindle and adapted to communicate with said high pressure fluid passage, pulsation chambers surrounding said spindle on opposite sides of the high pressure chamber, opposing valve seats between the respective pulsation chambers and the high pressure chamber, and an annular flexible valve surrounding the spindle and extending into the high pressure chamber between said valve seats, said valve being adapted by its elasticity to be held against either seat by unbalanced pressures on opposite sides thereof during the movement of the spindle in the direction to unseat it and adapted in the further movement of the spindle in said direction and upon the balancing of said pressures to immediately leave said seat and snap onto the opposite seat.

65 8. A milking machine pulsator comprising fluid passages adapted to communicate respectively with sources of high and low pressure, two fluid chambers and a conduit allowing communication at a regulated rate back and forth between them, means providing two air pulsation chambers adapted for connection with teat cups, and valve mechanism operable in one position to connect one pulsation chamber with said high pressure fluid passage and the other pulsation chamber

with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the operation of said valve mechanism, said bellows having a flexible wall comprising a cylinder of flexible material and a helical spring maintaining said material in plaited form and whose tension tends to maintain the bellows expanded, thereby requiring an exterior pressure to compress the bellows.

9. A milking machine pulsator comprising fluid 15 passages adapted to communicate respectively with sources of high and low pressure, two fluid chambers and a conduit allowing communication at a regulated rate back and forth between them, means providing two air pulsation chambers 20 adapted for connection with teat cups, and valve mechanism operable in one position to connect one pulsation chamber with said high pressure fluid passage and the other pulsation chamber with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the operation of said valve mechanism, and means to maintain said bellows in one of its extreme positions when the pulsator is disconnected from its actuating fluid source.

10. A milking machine pulsator comprising fluid passages adapted to communicate respectively with sources of high and low pressure, two fluid chambers and a conduit allowing communication at a regulated rate back and forth between them, means providing two air pulsation chambers adapted for connection with teat cups, valve mechanism operable in one position to connect one pulsation chamber with said high pressure fluid passage and the other pulsation chamber with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the operation of said valve mechanism, and means to maintain said bellows in one of its extreme positions when the pulsator is disconnected from its actuating fluid source, said means including a closed coil helical spring fixed to the movable wall of the bellows.

11. A milking machine pulsator comprising fluid passages adapted to communicate respectively with sources of high and low pressure, two fluid chambers and a conduit allowing communication at a regulated rate back and forth between them, means providing two air pulsation chambers adapted for connection with teat cups, valve mechanism operable in one position to connect one pulsation chamber with said high pressure fluid passage and the other pulsation chamber with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the oper- 75

ation of said valve mechanism, said bellows having a flexible wall comprising a cylinder of flexible material, a helical spring maintaining said material in plaited form and tending to maintain the bellows expanded, and a helical spring fixed to the movable wall of the bellows, said springs constituting a fixing device adapted, when the pulsator is not in operation, to maintain the bellows and the valve mechanism in a fixed position suitable for starting the pulsator.

12. A milking machine pulsator comprising fluid passages adapted to communicate respectively with sources of high and low pressure, two fluid chambers and a conduit allowing communication at a regulated rate back and forth between them, means providing two air pulsation chambers adapted for connection with teat cups, and valve mechanism operable in one position to connect one pulsation chamber with said high pressure fluid passage and the other pulsation chamber with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the operation of said valve mechanism, said bellows having a flexible wall comprising a cylinder of flexible material and a helical spring maintaining said material in plaited form and whose tension tends to maintain the bellows expanded, a tightly wound helical spring fixed at one end to the movable wall of the bellows, and a member on the spindle which the other end of said spring engages when the pulsator is not in operation, said springs constituting a fixing device adapted to maintain the valve in one end position thereof and the valve mechanism in suitable position for starting.

13. A milking machine pulsator comprising fluid passages adapted to communicate respectively with sources of high and low pressure, two fluid chambers and a conduit allowing communication at a regulated rate back and forth between them, means providing two air pulsation chambers adapted for connection with teat cups, and valve mechanism operable in one position to connect one pulsation chamber with said high pressure fluid passage and the other pulsation chamber with the low pressure fluid passage and in another position to reverse said connections, one at least of said fluid chambers being bounded by a movable wall of a bellows, which wall is also a wall of one of said pulsation chambers, said pressure reversals effecting contraction and expansion of the bellows and controlling the operation of said valve mechanism, means tending to maintain the valve mechanism in one of its end positions when the pulsator is disconnected from its source of actuating fluid, thereby creating a measurably asymmetry in the operation of the pulsator, and means to compensate for such asymmetry, said last named means comprising throttling members in said conduit providing greater resistance to fluid flow in one direction than in the other.

14. A milking machine pulsator comprising a valve casing having a longitudinal bore provided with valve seats, fluid passages adapted to communicate respectively with sources of high and low pressure, two fluid pulsation passages adapted for connection with teat cups, and valve mechanism operable in one position to connect one pulsation passage with said high pressure fluid

passage and the other pulsation passage with the low pressure fluid passage and in another position to reverse said connections, said valve mechanism comprising a valve spindle reciprocable in said bore and valves carried by the spindle, said spindle being adapted to move one valve toward its seat while another valve is being moved in a direction to unseat it, each valve having a seat-contacting surface which is movable relative to the spindle and which is held on its seat by the unbalanced pressures specified while the valve spindle is moving in the direction to effect its unseating and until the other valve is seated.

15. A milking machine pulsator comprising a valve casing having a longitudinal bore provided with valve seats, fluid passages adapted to communicate respectively with sources of high and low pressure, two fluid pulsation passages adapted for connection with teat cups, and valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle, said valves comprising flexible discs having seat contacting surfaces whose marginal portions are movable relative to the spindle and are held on their seats by unbalanced pressure while the valve spindle is moving in a direction to effect their unseating, said spindle being adapted, in moving in a direction to move one valve toward its seat, to effect the seating thereof before another seated valve is unseated by its limit of flexibility under existing pressure conditions being exceeded.

16. A milking machine pulsator comprising a valve casing having a longitudinal bore provided with valve seats, fluid passages adapted to communicate respectively with sources of high and low pressure, two fluid pulsation passages adapted for connection with teat cups, and valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle, each valve comprising an annular disc whose inner marginal portion is secured to and moves with the spindle, whose mediate portion is comparatively thin and flexible and whose outer portion provides a seat contacting member which is substantially thicker than the mediate portion, thereby providing a substantially elastic valve having a comparatively rigid seating portion.

17. A milking machine pulsator comprising a valve casing having a longitudinal bore provided with valve seats, fluid passages adapted to communicate respectively with sources of high and low pressure, two fluid pulsation passages adapted for connection with teat cups, valve mechanism operable in one position to connect one pulsation passage with said high pressure fluid passage and the other pulsation passage with the low pressure fluid passage and in another posi-

- tion to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle, and flanges carried by the spindle and adapted to engage and positively unseat the valves after a predetermined movement of the valve spindle.
18. A milking machine pulsator comprising a valve casing having a longitudinal bore provided with valve seats, fluid passages adapted to communicate respectively with sources of high and low pressure, two fluid pulsation passages adapted for connection with teat cups, valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle; said valves comprising annular discs whose inner marginal portions are secured to the spindle, said valve spindle and valve casing being adapted to be assembled by the insertion of the spindle axially into said bore, the valve discs being of such flexibility and elasticity as to enable them to distort sufficiently to be forced, in said assembly, through the annular valve seats.
19. A milking machine pulsator comprising a valve casing having a longitudinal bore provided with valve seats, fluid passages adapted to communicate respectively with sources of high and low pressure, two fluid pulsation passages adapted for connection with teat cups, and valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle, said valves comprising flexible an-
- 5 nular discs whose inner marginal portions are confined in grooves in the spindle and whose outer marginal portions are held on seats on the wall of said bore by unbalanced pressures as specified, until, in the movement of the spindle in the direction to unseat them, their limit of flexibility is exceeded.
20. A milking machine pulsator comprising a valve casing having a longitudinal bore provided with valve seats, fluid passages adapted to communicate respectively with sources of high and low pressure, two fluid pulsation passages adapted for connection with teat cups, valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle; said valves comprising annular discs whose inner marginal portions are secured to the spindle, said valve spindle and valve casing being adapted to be assembled by the insertion of the spindle axially into said bore, the valve discs being of such flexibility and elasticity as to enable them to distort sufficiently to be forced, in said assembly, through the annular valve seats.
21. A milking machine pulsator comprising a valve casing having a longitudinal bore provided with valve seats, fluid passages adapted to communicate respectively with sources of high and low pressure, two fluid pulsation passages adapted for connection with teat cups, valve mechanism operable in one position to connect one pulsation passage with said high pressure fluid passage and the other pulsation passage with the low pressure fluid passage and in another position to reverse said connections, said valve mechanism comprising a valve spindle reciprocable in said bore and valves carried by the spindle and having seat-contacting surfaces which are movable relative to the spindle and which are held on their seats by unbalanced pressures while the valve spindle is moving in the direction to effect their unseating and which are unseated at the completion of said valve-unseating movement of the spindle; the valve casing comprising a one-piece cylinder and the valves comprising annular discs whose inner marginal portions are secured to the spindle, said valve spindle and valve casing being adapted to be assembled by the insertion of the spindle axially into said bore, the valve discs being of such flexibility and elasticity as to enable them to distort sufficiently to be forced, in said assembly, through the annular valve seats, thereby allowing the cylindrical valve casing to be made in one piece as specified.

KARL GUNNAR MAGNI. 65

CERTIFICATE OF CORRECTION.

Patent No. 2,186,253.

January 9, 1940.

KARL GUNNAR MAGNI.

It is hereby certified that the name of the assignee in the above numbered patent was erroneously described and specified as "De Laval Separator Company" whereas said name should have been described and specified as The De Laval Separator Company, of New York, N. Y., a corporation of New Jersey, as shown by the record of assignments in this office; and that the said Letters Patent should be read with this correction therein that the same may conform to the record of the case in the Patent Office.

Signed and sealed this 19th day of March, A. D. 1940.

(Seal)

Henry Van Arsdale,
Acting Commissioner of Patents
